UNITED STATES PATENT OFFICE.

WILLIAM J. BALLARD, OF SPOKANE, WASHINGTON.

LUGGAGE-CARRIER.

1,318,751.

Specification of Letters Patent.

Patented Oct. 7, 1919.

Application filed February 5, 1919. Serial No. 275,181.

To all whom it may concern:

Be it known that I, WILLIAM J. BALLARD, a citizen of the United States, residing at Spokane, in the county of Spokane and State 5 of Washington, have invented certain new and useful Improvements in Luggage-Carriers, of which the following is a specifica-
tion.

The primary intent of the present invention is the provision of means whereby luggage may be safely and conveniently carried upon the running or foot board of an automobile or analogous vehicle, said luggage carrier being constructed and mounted so as to be folded into a small space and be out of the way when not required for immediate service and yet adapted to be adjusted for use when required without necessitating recourse to tools or other appliances.

20 The invention provides a luggage carrier embodying means whereby it is secured to the running board of a vehicle in such a manner that when the device is folded and not adjusted for service it is out of the way.
25 and does not interfere with the free use of the running board in the accustomed way.

The drawings illustrate a preferred embodiment of the invention. However it is to be understood that in adapting the same to meet different conditions, various changes in the form, proportion, and minor details of construction may be resorted to without departing from the nature of the invention as claimed hereinafter.

35 Referring to the accompanying drawings, Figure 1 is an edge view of a running board provided with a luggage carrier embodying the invention, said carrier being in operative position, the dotted lines at the 40 left showing a portion of the carrier as it appears when folded.

Fig. 2 is a view of the under side of the running board showing the luggage carrier in folded position.

45 Fig. 3 is an end view of the carrier provided with the standard having a clamp at its lower end, the running board being in section.

Fig. 4 is an end view of the carrier as seen
50 from the pivoted end.

Fig. 5 is a transverse section of the running board showing the luggage carrier in folded position thereunder, the parts being illustrated on a larger scale.

55 Fig. 6 is a view similar to Fig. 5, the lug-

gage carrier being in section in line with the barrel containing the operating spring.

Fig. 7 is a detail view of the means whereby the guards are secured when extended.

Corresponding and like parts are referred to in the following description and indicated in the several views of the drawings by like reference characters. 60

The numeral 1 designates a running or foot board such as commonly provided for 65 automobiles and kindred motor vehicles. The luggage carrier is mounted upon the running board 1 in a manner to fold thereunder so as to be out of the way and to extend vertically along the outer edge thereof when in 70 operative position to retain luggage thereon. Because of the length of running boards as ordinarily provided it is proposed to provide the luggage carrier in similar or like sections or parts, the one being a counter-part of the 75 other. In some instances the luggage carrier may consist of a single organization and this is particularly the case when the running board is comparatively short.

One of the structures or sections of the 80
luggage carrier will be described in detail
hereinafter and will suffice for a clear under-
standing of both structures, since corre-
sponding and like parts will be designated
by like reference characters. A bracket 2 85
is secured to the outer edge of the running
board 1 by means of a bolt 3. The bracket
2 is formed with an opening 5 for a purpose
to be explained more fully hereinafter. The
inner end of the opening 5 is enlarged and 90
internally threaded to receive a barrel or
tube 6. The opening 5 receives a rod 7 or
like member which is mounted to have a
limited rotary and longitudinal movement
therein. The rod 7 extends through the bar- 95
rel or tube 6 and has a cap 8 secured to the

inner end thereof. An expansible helical spring 10 mounted on the rod 7 is housed within the tube or barrel 6. The outer end of the spring 10 is connected to the bracket 2 and its inner end is engaged by the cap 8. The spring 10 exerts a two-fold pressure on the rod 7 the one longitudinally to move the rod 7 inward and the other torsionally to rotate the rod 7 to hold its outer portion 12 in vertical position as indicated most clearly by the full lines in Fig. 1 and the dotted lines in Fig. 5. The bracket 2 has a projecting part 13 which constitutes a stop shoulder or ledge to limit the downward movement of 110

the part 12 when lowered into horizontal position preliminary to folding the carrier beneath the running board 1. The part 12 is disposed at a right angle to the rod 7 and 5 preferably constitutes an integral part thereof, being formed by bending a rod upon itself at a right angle. The element 12 constitutes a supporting arm or standard to which the guard portion of the carrier is attached.

The guard comprises a lazy tongs structure 14 which may be of any ordinary construction comprising pivotally connected strips or bars. Clips 15 and 16 are loosely 15 mounted upon the arm or standard 12 and the lazy tongs 14 is connected at its inner end thereto. The lazy tongs is adapted to fold, as indicated most clearly in Figs. 2 and 5 and to be extended, as indicated in Fig. 1. 20 When the lazy tongs is extended and in operative position it is disposed along the outer edge of the running board 1 so as to retain luggage thereon between the guard and the apron 17 or like part along the inner edge 25 of the running board. The lazy tongs is adapted to turn on the arm 12 so as to swing into a position to come beneath the running board 1. When the lazy tongs is in folded position its end is engaged by a holder 18 30 which is secured to the under side of the running board. A bar 19 extending lengthwise of the running board is secured at one end thereto and at its opposite end to the barrel or tube 6 and has the holder 14 attached thereto. A spring 21 disposed within the holder 18 exerts a pressure upon the folded guard to prevent rattle. The end of the guard is retained in the holder 18 by the expanding tension of the spring 10 and 35 this action of the spring 10 also serves to hold the lower end of the arm 12 on the stop shoulder or ledge 13. The torsional action of the spring 10 holds the guard against the under side of the running board and likewise tends to hold the guard in vertical position when adjusted for service. When the arm 12 is drawn outward, to clear the outer edge of the running board, it is turned into vertical position and is retained in such position by the torsional action of the spring 10. The bracket 2 constitutes a stop to limit the upward movement of the arm 12 when it assumes a vertical position. When the arm 12 is drawn outward the inner end of the 50 folded guard is withdrawn from the holder 18 and said guard turns upon the arm 12 and assumes a pendent position, thereby admitting of the arm and guard being swung into an upright position along the outer or 55 front edge of the running board. The guard is then extended the required distance and is made secure at its free end. As indicated most clearly in Fig. 1 the guard comprises two similar or like structures and the free 60 ends of the lazy tongs are provided with 65

complemental fastening means, whereby to secure the guards when extended.

The outer ends of the members forming the lazy tongs of each guard are provided with supplemental fastening means whereby to secure them when the guard is adjusted into operative position. A standard 22 is provided for supporting the outer ends of the lazy tongs and is preferably attached to one of the lazy tongs structures and detachably connected with the companion lazy tongs structure. The standard 22 is provided at its lower end with a clamp 23 whereby it may be detachably connected with the outer edge portion of the running board 1. 70 The upper portion of the standard 22 is offset outwardly so as not to interfere with the lazy tongs and admit of their alinement when in operative position. A clip or bracket 24 is mounted upon the upper portion of the 80 standard 22 and a bar 25 is connected thereto and projects vertically. Horizontal members 26 and 27 are attached to the ends of the vertical bar 25 and each comprises supplemental bars or elements which are transversely spaced. One of the lazy tongs structures is permanently connected to corresponding ends of the members 26 and 27, whereas the other lazy tongs structure is detachably connected with the remaining ends 90 of the members 26 and 27 as shown most clearly in Fig. 7. The free ends of the elements or bars comprising the member 27 are connected by a pin or fastening 28. The free ends of the bars or elements comprising the 95 member 26 are connected by means of a bolt 29 which is provided with a thumb nut whereby said elements or bars may be drawn together to clamp the element of the lazy tongs placed therebetween. One element of 100 the lazy tongs is formed with a lateral notch 105 30 which receives the bolt or fastening 29. The other element of the lazy tongs is provided with a hook 31 which is adapted to engage the fastening 28. In this manner the 110 lazy tongs may be readily connected or disconnected as may be required. When the lazy tongs are disconnected, as indicated most clearly in Fig. 7 each may be folded beneath the running board, as indicated in Fig. 2, the 115 standard 22 folding with the lazy tongs to which it is attached. When it is required to fold the carrier the contiguous ends of the lazy tongs are disconnected after which the guard is folded about, as indicated in Fig. 120 2, the arm or standard 12 being turned from a vertical position into a horizontal position and the guard 14 being swung from a vertical position into a horizontal position and adjusted so that its free end will engage 125 the holder 18 and upon releasing the arm 12 the spring 10 will act to move the rod 7 inward and thereby bring the arm 12 over the shouldered portion 13 of the bracket and press the end of the guard 14 into the holder 130

and retain the parts in folded position. Strap loops 32 are applied to the upper ends of the arms or standards 12 to receive straps whereby luggage may be fastened on the 5 running board.

The provision of the standard 22 enables the left hand carrier to be used solely as means for retaining luggage on the running board of an automobile particularly when 10 such running board is comparatively short. However, when the running board is of the length such as usually provided for automobiles having front and rear seats it is desirable to provide the luggage carrier in 15 two similar or like sections substantially as herein indicated.

The foregoing description and the drawings have reference to what may be considered the preferred, or approved, form of 20 my invention. It is to be understood that I may make such changes in construction and arrangement and combination of parts, materials, dimensions, et cetera, as may prove expedient and fall within the scope 25 of the appended claims.

Having thus fully described my invention, what I claim as new and desire to secure by Letters Patent is:—

1. A luggage carrier for the running 30 board of a vehicle, the same comprising a pivoted arm and a guard mounted on the arm to move therewith and having an independent movement to swing beneath the running board into folded position when 35 the arm occupies a horizontal position.

2. A luggage carrier, comprising an arm, a folding guard mounted upon the arm, a holder for engaging the end of the guard when the latter is folded, and means for 40 holding the guard in engagement with the said holder.

3. A luggage carrier, comprising an arm having a pivotal and a lateral movement, a folding guard mounted upon the arm, a holder for receiving the end of the guard 45 when folded and a spring coöperating with the arm and guard to retain the latter in engagement with the holder.

4. In combination with the running board of a vehicle, a clamp, a rod mounted in the 50 clamp beneath the running board to receive a pivotal and a longitudinal movement and having an arm at its outer end to project upwardly in front of the running board, a spring mounted upon the rod and normally 55 tending to hold the arm in vertical position and to move the same inward and a guard mounted upon the arm to extend along the front edge of the running board and adapted to be folded beneath the running board when 60 not required for immediate service.

5. A luggage carrier, comprising a bracket having a portion formed with an opening and a projecting shoulder, a rod mounted in the opening of the bracket to turn and move 65 longitudinally therein and provided at its outer end with an arm adapted to engage the shouldered portion of the bracket, an expansible helical spring mounted on the rod and having one end engaged by the 70 bracket and its opposite end connected with the rod and normally tending to turn the rod and move the same longitudinally, and a folding guard mounted upon the said arm 75 to swing thereon.

In testimony whereof I affix my signature in presence of two witnesses.

WILLIAM J. BALLARD.
